1,973,770

PORTABLE GOLD WASHING AND CONCENTRATING MACHINE FOR PLACER SANDS AND QUARTZ ORES

William A. McCullough, San Quentin, Calif.

Application May 29, 1933, Serial No. 673,424

5 Claims. (Cl. 209—14)

This invention is a portable gold washing and concentrating machine for placer sands and quartz ore, and is especially directed to a concentrating unit which will make an unusually high recovery of gold and valuable minerals with very low consumption of power and water, and also, to a unit of the knockdown type in which the individual elements are light in weight and readily transportable by mule back into substantially inaccessible regions with but little difficulty.

This invention will operate efficiently on crushed ores, sands or gravel, making a high recovery of values, especially that of free or native gold and other precious metals in the native state.

The unit is compact, having unusual capacity in relation to the limited space required, since one of these units requiring a floor space of only thirty-six square feet will efficiently recover all gold, including flour and flake gold or dust, and will treat approximately fifty cubic yards of material in ten hours, as substantiated by actual tests, and with an expenditure of only about two horsepower.

The unit combines the features of screening, classification, jiggling, sluicing, and amalgamation, and thereby provides a recovery far beyond that attained by any known devices, and this is due to the special arrangements and combinations of the various elements making up the unit.

The main object of the invention, therefore, is to provide a concentrating unit of compact type having unusually high efficiency in the separation of the values and gangue in sands, gravels and crushed ores.

Another object of the invention is to provide a unit as outlined which will produce a product of high concentration and provide high recovery, of precious metals especially.

A further object of the invention is to provide a unit as outlined which is economical in its consumption of both power and water, and in which the individual elements are readily and quickly replaceable and transportable.

A still further object of the invention is to provide a unit which combines the features of screening, classification, jiggling, sluicing, gravity separation and amalgamation, whereby maximum recovery of values is provided.

A still further object of the invention is to provide a unit with screens in which a portion of the fines passing through each screen is separated from the balance of the fines and individually treated to a jiggling and amalgama-

tion process whereby the efficiency of the unit is increased, both as to capacity and recovery.

Other objects and advantages of the invention will become apparent as the following description is read on the drawings forming a part of this specification, and in which similar reference characters are used to designate similar parts throughout the several views, of which:

Fig. 1 is a perspective view of the invention with related distributing feeder and grizzlies.

Fig. 2 is a side elevation of the invention.

Fig. 3 is a front elevation of the invention.

Fig. 4 is a plan view of the invention.

Fig. 5 is a transverse sectional elevation through one of the sluices.

Fig. 6 is a section taken on line 6—6 of Fig. 5.

Fig. 7 is a plan view of one of the combined screens and amalgamating basins.

Fig. 8 is a section taken on line 8—8 of Fig. 7.

Fig. 9 is a plan view of the amalgamating pan.

Fig. 10 is a section taken on line 10—10 of Fig. 9.

The invention consists of a frame or cradle comprising a base 20 having integral rockers 21, which ride in rails 22, which are mounted in a platform or foundation 23, the entire unit being supported on these rockers.

Removably secured to the base 20 are standards 24, to the top of which, a head or cap 25 is removably secured, the various members of the base 20 and head 25 also being removably secured together, such as by bolts. Suitable bracing for the cradle or frame is provided as indicated at 26 which shows cables or rods with adjusting or tightening means 27, these cables or rods being attached at their ends to hooks 28 and 29 fixed respectively in the base 20 and head 25.

The amalgamating pan and the screen supports consist of rollers 30 which are rotatably mounted on stub shafts 31, which are adjustable in a vertical plane by means of the threaded rods 32, either by nuts 33 or by threading the holes in the shafts 31, in which case, rotation of the rods will coincidentally adjust the entire series of screens, either for inclination or height. By adjusting the center roller above and out of alignment with the side rollers, both rocking and reciprocating motion are given to the screens.

The combined screens and amalgamators each consist of a frame 34, the flanged portions 35 of which ride on the rollers 30. Secured to the bottom of the frame 34 is an amalgamating basin 36 having an opening 37, the basin proper consisting of the portion extending from the tail

end or discharge end 38 to the lower end 39 of the opening 37, this portion being coextensive with a minor portion of the length of the screen, as shown.

5 The amalgamating basin as shown, consists of the water-tight portion between 38 and 39 and which is provided with the bar riffles 40, between which mercury pools are formed, or the riffle structure may be made similar to the sluice riffle system as shown in Figs. 5 and 6. The screen 41 is mounted in spaced relation above the top of the riffles 40, and an opening is provided at 42 to permit the gangue to slough through after the values are gathered by the mercury 43, and the 15 heavier fragments settle.

It will be noted that the screens are of increasingly finer mesh with the downward flow, and that the material passing through the screens over the openings 37 drops to the next screen 20 below which is of finer mesh. The portion passing through the screen over the basin is trapped between the riffles 40, the native precious metals are amalgamated with the mercury and the higher specific gravity ores, due to the jiggling 25 action, which will be later described, are retained, while the gangue, being of lower specific gravity, gradually works up, over, and out through the opening 42 and discharges either into a sluice or to the next screen below. All 30 screens and basins are formed alike, except as to mesh of screen and form and height of riffles, and all are amalgamated. A discharge lip 44 is provided at the tail end of each screen, and a clevis is secured to the head end as shown at 45 35 for connection to the reciprocating means.

The amalgamating pan consists of an amalgamated copper pan 46 having vertically staggered riffles, preferably formed of round copper bars, and spaced from the bottom 48 of the pan 46, a 40 suitable supply of mercury being deposited in the pan for amalgamating the values in the ore.

The amalgamating pan is mounted adjacent the bottom of the cradle, and the screens are 45 vertically spaced and superposed in relation to the pan and to each other, and each basin receives a certain proportion of the fines passing through its screen and thereby increases the capacity and efficiency of the unit, and makes unusually high recovery possible with a minimum of floor space and weight.

The sluices consist of sluice boxes 49 which are removably mounted on the standards 24, in 50 cooperative relation to the tail ends of the screens and receive the discharge or tailings therefrom.

Each sluice consists of the box 49, with a removable riffle unit, consisting of side members 50, grids or grizzlies 51 and riffles 52, a suitable supply of mercury being supplied to each riffle and the riffles and box being made of copper 60 and amalgamated.

A suitable supply of water 53 is provided for the screens and sluices and the material is fed from a suitable supply over grizzlies 54, over the 65 distributing feeder 55, onto the top screen, a portion of the fines passing through the opening 37 to the next screen below, and the remaining portion being intercepted by the amalgamating basin, oversize from the screen and reject from 70 the basin being received by the sluice. The series of sluices discharge one into the other the bottom screen discharging a portion of its fines into its basin and the remainder into the amalgamating pan 46, where final separation is 75 effected.

The frame or cradle is rocked by means of eccentrics 56 operating at both ends of rockers 21. The eccentrics are mounted on shafts 57 and 58 which are driven by a pulley 59 or other means, through a shaft 60, through bevel gears 61 and 62. This provides a rocking motion for the frame together with all of its associated parts, relative to one vertical plane taken on the vertical center line of Fig. 3.

The screens are reciprocated by means of connections 62' operating on eccentrics 63 which are affixed on the vertical shafts 64, which in turn are rotatably mounted in bearings 65 supported in brackets 66. A universal joint 67 is provided for each shaft to compensate for the 85 rocking motion of the cradle, shafts 64 being driven by the shafts 60 and 68 through bevel gears 70, and shaft 68 being driven through bevel gears 69.

Thus it will be noted that while the frame and 90 all associated parts are rocked relative to one plane, the screens are reciprocated across a vertical plane at right angles thereto, both motions being independent of each other, and rocking and reciprocating motion, or rocking motion 95 in two planes and reciprocating motion in one of the planes is provided for the screens, and rocking motion in one plane for the amalgamating pan.

It will be understood that variations in construction and arrangement of parts which are consistent with the appended claims may be resorted to without detracting from the spirit or scope of the invention or sacrificing any of the advantages thereof.

I claim:

1. A concentrator unit comprising a frame, an amalgamating pan mounted in the lower portion of said frame and provided with a series of riffles, a series of classifying screens adjustably mounted in superposed relation to said pan and to each other, an amalgamating basin having riffles and mounted beneath the tail portion of each screen to catch fines passing through the screen adjacent the discharge end thereof, an amalgamating sluice having riffles and mounted in cooperative relation to the tail end of each screen to receive the tailings therefrom, adjusting means for coincidentally adjusting the pitch of all of said screens, means imparting a rocking motion to said unit in one plane, and means imparting a reciprocating motion to said screens in another plane.

2. A concentrator unit comprising a frame, an amalgamating pan mounted in the lower portion of said frame and provided with a series of riffles, a series of classifying screens adjustably mounted in superposed relation to said pan and to each other, an amalgamating basin having riffles and mounted beneath the tail portion of each screen to catch fines passing through the screen adjacent the discharge end thereof, an amalgamating sluice having riffles and mounted in cooperative relation to the tail end of each screen to receive the tailings therefrom, adjusting means for coincidentally adjusting the pitch of all of said screens, rocking means cooperating with said unit for rocking said unit relative to one plane, and reciprocating means cooperating with said screens for reciprocating said screens transversely of the rocking movement of said unit, whereby rocking motion is provided for the sluices and amalgamating pan, and rocking and reciprocating motion in right angular relation to each other are provided for the screens.

3. A concentrator unit comprising a frame, an amalgamating pan mounted in the lower portion of said frame, a series of collectively adjustable screens superposedly mounted relative to said pan and to each other, an amalgamating basin mounted beneath the tail portion of each screen catching fines from the lower portion of the screen, an amalgamating sluice for each screen, rocking means cooperating with said unit for 10 rocking said unit relative to one plane, and reciprocating means cooperating with said screens for reciprocating said screens transversely of the rocking movement of said unit. 4. A concentrator unit comprising a frame, an amalgamating pan mounted in the lower portion of said frame, a series of collectively adjustable screens superposedly mounted relative to said pan and to each other, an amalgamating basin mounted beneath and in cooperative relation to the tail portion of each screen catching fines from the lower portion of the screen, and means coincidentally rocking said unit about one 15 20
- vertical plane and reciprocating said screens across a vertical plane at right angles to said one plane. 5. A concentrating unit comprising a frame supported on rockers, an amalgamating pan mounted adjacent the bottom of said frame, a series of vertically spaced, adjustably inclined screens reciprocally mounted in said frame in superposed relation to said pan, an amalgamating basin mounted beneath each screen in cooperative relation to the portion of the screen adjacent the discharge end to receive fines passing through that portion of the screen, an amalgamating sluice mounted in cooperative relation to the tail end of each screen, means for rocking said frame, and means for reciprocating said screens in a plane transversely to their rocking motion, said screens being mounted on rollers, and releasing means for releasing said screens and pans to permit convenient removal thereof from the frame for cleanup. 80 85 90 95
